ICE BUCKET

Ralph B. Billig, Westlake, and Manuel S. Ziskin,
Mayfield Heights, Ohio

Application November 8, 1957, Serial No. 48,391

Term of patent 14 years

(Cl. D58—17)

FIG. 1

Fig. 1 is a top plan view of an ice bucket, showing our new design; and

Fig. 2 is a side elevational view thereof.

The side not shown is the same as the side shown.

The drawing is shaded to indicate contrasting colored areas.

We claim:

The ornamental design for an ice bucket, as shown and described.
